UNITED STATES PATENT OFFICE

167,159

SLIPPER OR SIMILAR ARTICLE

Pauline D. Ney, Santa Monica, Calif., assignor to Paddies Incorporated, Santa Monica, Calif., a corporation of California

Application March 17, 1952, Serial No. 18,931

Term of patent 14 years

(Cl. D7—7)

To all whom it may concern:

Be it known that I, Pauline D. Ney, a citizen of the United States, residing in Santa Monica, in the county of Los Angeles, State of California, have invented a new, original, and ornamental Design for a Slipper or Similar Article, of which the following is a specification, reference being had to the accompanying drawing, forming a part thereof.

I claim:

The ornamental design for a slipper or similar article, substantially as shown.

PAULINE D. NEY.
